Inventor,

Stewart Taylor

By John W. Thacker
Attorney.

UNITED STATES PATENT OFFICE.

STEWART TAYLOR, OF HYDE PARK, ILLINOIS.

SKID.

SPECIFICATION forming part of Letters Patent No. 288,276, dated November 13, 1883.

Application filed April 11, 1883. (No model.)

To all whom it may concern:

Be it known that I, STEWART TAYLOR, a citizen of the United States, residing at Hyde Park, in the county of Cook and State of Illinois, have invented a certain new and useful Improved Skid, which is fully described in the following specification, reference being had to the accompanying drawings, in which—

Figure 1 represents a perspective view of my improved skid; Fig. 2, a transverse sectional view, taken at the line *a a*, Fig. 1. Fig. 3 is a vertical sectional view of the end of one of the rails, showing a side view of the end piece and end of the web. Fig. 4 is a sectional view of a portion of one of the end pieces and rail and web, showing the manner in which the end piece is attached to the web; and Fig. 5 is a transverse sectional view of the web and rail, showing a modified form of the rails of the skid.

The same letters denote the same parts in all the figures.

The object of my invention is to make a light, strong, cheap, and durable skid, to be used in handling heavy articles in loading and unloading wagons, cars, and for analogous purposes; and my invention consists in a metallic skid having rails, on which the freight rests, supported and strengthened by a metallic web, and also in attaching to the ends of the rails and web end pieces, which are hereinafter fully described; and it also consists in combining with the web the braces in the manner hereinafter fully specified.

To enable others to understand fully the construction and operation of my invention, I will describe the same with particularity.

A represents the rails of the skid, or that portion of a skid on which the articles that are being loaded and unloaded rest. These rails are metallic rails.

B are metallic webs, connected to the under side of the rails in such a manner as to strengthen them and keep them from bending when supporting heavy weights. In Figs. 1 and 2 the rails are shown in tubular form, slotted lengthwise on one side, which slot receives the edge of the web, and the webs and rails are connected together by means of rivets or bolts *C*, passing through them. These rails may be rolled with the web in the form shown in Fig. 5, when the rivets or bolts can be dispensed

with, excepting the one which secures the end pieces, hereinafter specified, to said web and rail.

D are hooked end pieces, which are secured to the ends of the webs and rails by means of rivets or bolts, as clearly shown in Figs. 3 and 4. The hooks on these end pieces are for the purpose of holding the skid in place when in use, as the hooks hook upon the wagon or car, or the elevated platform or floor from which the freight is being removed or to which it is being delivered. These end pieces should be strong and durable, and I preferably make them of metal, so that they will be durable.

E are cross-braces which permanently secure the two webs of the skid together, and are made in such form as to hold them vertical to each other. The form of these braces is clearly shown in Figs. 2 and 5 of the drawings. These are of metal, and preferably made of malleable iron, and cast with shoulders *F* near their ends, and passing through holes in the webs, and then the ends *G* are headed down, as clearly shown, making a permanent attachment, and each brace being connected with the webs at four points, bracing the webs at both top and bottom, so as to hold them solidly in place.

The rails at the opposite end from that to which the hooked end pieces are attached are flattened, as shown at *h h*, for the purpose of more readily receiving and delivering freight that is passed upon them.

There are great numbers of these skids used in handling freight—such as boxes, barrels, &c.—and it is very important that they should be strong, light, and durable.

Having thus fully described my invention, what I claim as new, and desire to secure by Letters Patent, is—

1. The rails *A* and webs *B* in a skid, substantially as and for the purpose specified.
2. The rails *A* and webs *B* and hooked end pieces, *D*, in a skid, substantially as specified and shown.
3. The rails *A* and webs *B* and braces *E*, combined and operating in the skid, substantially as specified and shown.

STEWART TAYLOR.
